UNITED STATES PATENT OFFICE.

ROBERT M. DIXON, OF EAST ORANGE, NEW JERSEY.

WINDOW.

No. 820,958.

Specification of Letters Patent.

Patented May 22, 1906.

Application filed February 11, 1905. Serial No. 245,196.

To all whom it may concern:

Be it known that I, ROBERT M. DIXON, a citizen of the United States, residing at East Orange, county of Essex, and State of New Jersey, have invented certain new and useful Improvements in Windows, of which the following is a specification.

This invention relates, broadly, to improvements in window constructions, but is particularly directed to car-windows or other movable structures.

One of its objects is to provide a simple and effective construction which is especially adapted to withstand the damaging effects due to the jolting and vibrations had in railroad cars.

Another object is to provide means for locking the sashes employed in the windows of railway-cars or other movable structures such that while the sash is positively and securely locked in any predetermined position the same may be readily moved to an opened or closed condition.

Other objects will be in part obvious and in part pointed out hereinafter.

The invention accordingly consists in the features of construction, combinations of elements, and arrangements of parts, which will be exemplified in the construction hereinafter described and the scope of the application of which will be indicated in the appended claims.

In the accompanying drawings, Figure 1 is a front sectional elevation of a window with the invention therein embodied, portions of interposed features being broken away to more clearly show certain normally concealed details of the construction. Fig. 2 is a section taken along a plane transversely intersecting Fig. 1 along line 2-2 thereof, showing the manually-operable means for actuating the release mechanisms. Fig. 3 is a vertical section taken along line 3-3 of Fig. 1 to show certain other details of the said releasing mechanism. Fig. 4 is a horizontal section taken along line 4-4 of Fig. 1, showing details of the kerfed stile of the sash and the mode of interfitting the same to the jamb of the frame.

In such drawings like characters of reference denote corresponding parts through all the views thereof.

In carrying out this invention a sash *a* is slidably mounted in a suitable frame in a suitable manner, as between the jambs thereof. The mode of suspending the sash which is adopted by this invention aims at a con-

struction in which chattering or other objectionable action of like nature will be avoided during the raising and lowering of the sash. To this end an equalization-bar *b'* 60 overlies the upper end of the sash and is connected thereto at an intermediate point by some pivotal means, such as a bolt *b*², which is shown in a median position with regard to the ends. Flexible sash-supporting straps *b* 65 run from a suitable sash-balance *c*, so adjusted as to normally overcome the weight of the parts carried thereby, and such balance may either comprise the ordinary well-known weights or consist of a special spring construction, as may be preferred. These straps are usually detachably affixed to said equalization-bar at the ends thereof and through the medium of such bar serve to automatically support the sash depending therefrom. 70 It will be observed that this construction permits of a considerable irregularity in the pull of the straps at each end without producing a corresponding swaying of the balance.

In the ordinary construction one difficulty 80 has obtained in that the vertical ends of the sash generally tend to move at an uneven rate, and accordingly either one side or the other of the sash will intermittently wedge, so as to produce the objectionable chattering 85 familiar to all those who have ever manipulated a sash. This is particularly noticeable in railroad structures, inasmuch as dirt and cinders very considerably augment the sliding friction along the sides of such sash. By 90 virtue of this novel means the entire pull on the window occurs at the middle point, from which the stresses are accordingly evenly distributed and the objectionable lateral vibration and resultant friction thereby avoided. 95

Another novel feature of this invention resides in the construction of the sash-stile, which is not only arranged to slidably interfit with the jamb, but also affords a support for a sash lock or clog which is so carried thereby 100 as to be adapted to be moved normally against the jamb in such a way as to prevent relative movement between such parts.

In the specific embodiment which has been here selected for explanatory purposes 105 the sash-stile has a U shape, being made in the form of a channel-bar, as shown by *a* in Fig. 4. This arrangement affords a suitable channel or kerf within which may be positioned the clog means, as will be presently 110 described more specifically, and it is also advisable to mount the equalization-bar within

such channel at the upper end of the sash, thereby producing a compact expedient.

- This invention also provides on the frame jamb-strip e^2 , which is shown as separate therefrom, and such jamb-strip is so contoured as to slidably interfit with the sash-stile, preferably by protruding into the above-mentioned kerf or channel, as will be apparent from an inspection of Fig. 4. This 10 jamb-strip provides the contact-surface for the locking means or clog to abut against and to more certainly prevent any initial slipping between such surfaces. Side beads a' and a^2 may also be provided to effect a 15 more complete closure between the sash-stile and the jamb-strip. It will be noted that this arrangement is dust-proof to a high degree and, furthermore, that it may be conveniently and economically constructed. 20 An additional advantage accruing to this arrangement resides in the fact that the jamb-strip e^2 may be readily replaced when worn to an extent sufficient to interfere with the action of the clog, which will now be described. 25 The clog comprises a wedge-shaped member e , which is mounted upon and carried by the sash and is adapted for being forced against the jamb-strip e^2 with such force that sufficient sliding friction is set up to effectively 30 resist a sliding movement of the sash with respect to the frame. Such clog e is advisably of a considerable length in order that its sliding contact with the jamb will be as great as possible and be so distributed as to insure a 35 smooth action during the movement of the sash. Provision is also made for forcing such clog against the slide, so that all portions of the contacting surfaces will evenly abut, and to this end the vertical wall d of the 40 channelled sash is inclined in such a way that the channel has a greater depth at the top than at the bottom. The clog is preferably inclined on its inner surface at an angle corresponding to the inclination of the sash-channel. 45 The effect of having these abutting surfaces inclined in the direction shown is to prevent the sash from being inadvertently raised through the tension of the suspending cords or straps b . As the friction of the clog 50 against the jamb is sufficient to prevent the clog from moving under a moderate pull and as the sash is always tending to rise independently of such clog, it will be clear that because of the inclination given to the abutting 55 faces of the clog and sash, respectively, an initial upward movement of the sash will forthwith translate the clog so as to force it against the jamb with a force directly proportional to the extent of the mutual movement between the sash and clog. 60 As a result the continued elevation of the sash under the tension of the straps is at once frictionally resisted and to a degree that precludes any possibility of an upward movement of 65 any substantial extent. It will be noted,

moreover, that the clog has a greater extent of its surface engaged with the frame than with the sash-stile, as clearly shown in Fig. 1, which construction is preferably secured by removing a portion of the surface thereof adjacent said sash. The downward movement of the sash is, however, mainly controlled by the supporting-straps, the tension of which will be so adjusted as to slightly overbalance the weight of the sash. 75

It will be noted that the clog is so mounted upon and carried by the sash that it moves in the plane of the sash. This has certain advantages over having it move along other planes—as, for instance, transversely to such 80 sash-plane or along planes parallel to the sash-plane—since the stresses are all directed against the sash-stile of the sash, so that they are ultimately resisted by the jambs and not by beads fixed to the jambs and to the sides 85 of the sash-stiles. In this way clogs may be mounted upon opposite vertical edges, so as to mutually oppose the pressure of one another directly through the sash. Furthermore, by mounting the clog in the plane of 90 the sash it is possible to position the clog in a recess in the edge, and thereby preserve the original thickness of the clog to the complete elimination of any protruding parts, resulting in a compact entity not had in prior constructions. 95

It will now be evident that some means should be furnished for momentarily disengaging the clog whenever it is desired to alter the position of the sash in the window. 100 Among the expedients for this purpose falling within the contemplation of this invention may now be mentioned a highly-satisfactory and simple instrumentality which will usually be mounted in the lower portion 105 of the sash, which is suitably recessed for the purpose, as indicated by Figs. 1 to 3, inclusively. A bell-crank lever h is fulcrumed at i to a suitable lug extending from the bottom rail and has a bifurcated end g , 110 affixed to a lower extension from the clog. Upon swinging the bell-crank lever to the right the lower arm will correspondingly elevate the clog, and because of the bifurcated end the pin f will always be in engagement with the lever, which is turned by means of the actuator-rod k , which at the one end is pivoted to said lever and at the other is slidably journaled within a suitable standard l . 115 As it is highly desirable to have the clog in its normal position in locking engagement with the side of the jamb, an expansile spring r is interposed between a suitable abutment on the rod and the aforesaid standard in order 120 that such rod will normally be translated toward the clog, whereby through the instrumentality of the bell-crank lever such clog will be depressed under the influence of the spring and maintained in tight frictional en- 125 130

gagement with the jamb of the frame. It is perhaps conducive to clearness in this connection to recall attention to the fact that these parts are all mounted upon the sash, so as to be carried thereby in its movements, though it will be observed that such parts may at the same time have independent movements of their own.

This invention also provides a coöperant locking means for positively securing the sash in its lowermost or any other predetermined position. Such locking means consists of a bar *s*, which is reciprocatorily mounted in standard *l*. A spring *r* abuts the standard and a fixed collar on said rod and normally translates the same against the jamb, which will preferably be provided with an orifice for its reception, as shown by Fig. 1.

As it will be convenient to actuate all of the aforesaid parts into a non-locking position by manual means, this invention provides finger-levers *v* and *p*, which are fulcrumed at *w* and *q*, respectively, and so shaped as to protrude through side orifices had in an operating-handle *o'*. At their other ends such finger-levers engage within suitable seats or sockets provided by the actuator-rod and lock-bar, respectively, as indicated on the drawings by *t* and *m*. These inner ends *u* and *o* of the finger-levers are shown in proper place more clearly by Fig. 2.

The operation of the device may now be readily followed. To raise the sash, the protruding ends of the finger-levers are pressed together, and as a result the locking-bar *s* and the actuator-rod *k* are simultaneously drawn away from the corresponding jambs, thereby entirely freeing the sash with respect to the positive lock and at the same time elevating clog *e* to such an extent that the sash is no longer frictionally secured in place, and it may then be freely raised, carrying with it all of the parts, as aforesaid. When the desired height has been attained, the fingers are removed and the clog through the instrumentality of spring *r* is translated downward and because of its inclined edge is simultaneously forced against the side of the jamb. The friction afforded will be sufficient to restrain the clog against further movement; but should an initial upward movement of the sash take place the latter would move relatively to the wedge-like clog, which is retained against the side of the jamb, because of the friction. It is clear, however, that such upward movement would be slight in extent, because of the progressively-increasing resistance thereto attained through the action of the clog. A downward movement may, however, be had, since the effect thereof is to relatively move the clog and sash side in what may be termed a "downhill" direction, and as the clog is thus moved away from the jamb no friction will oppose the closing of the sash, and the only

resistance encountered will be the overbalancing tension of the suspending-straps *b*.

It will thus be seen that the herein-described invention is one well adapted to realize the several stated objects and ends. The sashes are self-contained mechanisms of a unitary nature, which are adapted to be made at any place and quite independently of cars undergoing construction, to which they may be subsequently applied with no difficulty. Moreover, should any one of such operative units become disordered in a car during service it may be easily and quickly replaced in any locality without tying up the whole car, as would be necessary in other expedients. In usage the sash may be manipulated with every ease, and it will withstand hard service with little deterioration. Furthermore, the various parts are disposed in an exceedingly-compact form, and the operative features are so concealed from view that a neat and pleasing appearance is preserved to the whole without, however, interfering with a ready access thereto for purposes of repair or replacement. The preferred form and arrangement has been shown; but the invention is not to be limited thereto, since while the same embodies the most improved type other deviations might be made at the sacrifice of certain of the advantages attained by the present structure. Also certain other embodiments of the invention might be made in view of this disclosure, as will be manifest to those skilled in the art, which would perform all the functions of the construction here shown and in substantially the same way, but without altering the character of this invention.

As many changes could be made in the above construction and many apparently widely-different embodiments of my invention could be made without departing from the scope thereof, I intend that all matter contained in the above description or shown in the accompanying drawings shall be interpreted as illustrative and not in a limiting sense.

Having described my invention, what I claim as new, and desire to secure by Letters Patent, is—

1. In a window construction, a frame, a sash slidably mounted between the jambs thereof, a wedge-shaped clog interposed between a stile of such sash and a jamb and carried by said sash and in frictional engagement with both of said parts, and means tending to raise said sash and simultaneously actuate said clog to prevent such movement.

2. In a window construction, a frame, a sash slidably mounted between the jambs thereof, and provided in its side stile with a groove having a greater depth at the top than at the bottom thereof, a clog interposed between the bottom wall of said groove and said jamb and having a wedge shape in con-

formity therewith and means normally maintaining said clog in a tightly-wedged position whereby sliding of said sash will be prevented.

5 3. In a window construction, a frame, a sash slidably mounted between the jambs thereof, wedge means interposed between and engaging directly said sash and frame to normally positively lock the same against an upward movement but unadapted to positively secure the same against downward movement, and means yieldably supporting said sash whereby the same may be manually lowered in opposition thereto.

15 4. In a window construction, a frame, a sash slidably mounted between the jambs thereof, a side stile of said sash provided with a groove which gradually diminishes in depth from the top to the bottom thereof, 20 a clog wedge-shaped in conformity with the bottom wall of said groove and interposed between the jamb and said wall, said clog being mounted to normally move against said wall within the plane of said sash and 25 means for releasing said clog.

5. In a window construction, a frame, a sash slidably mounted therein, an equalization-bar hinged to said sash, and sash-supporting cords attached to the ends of said 30 bar and adapted to support the same together with the sash suspended therefrom.

6. In a window construction, a frame, a sash slidably mounted therein, an equalizing-bar affixed to said sash at a point intermediate its ends, and suspending means supporting said bar and depending sash.

7. In a window construction, a frame, a sash slidably mounted between the jambs thereof, an equalization-bar overlying the 40 top end of said sash and attached thereto at a point intermediate its ends, and supporting-cords attached to the ends of said bar, whereby the same, together with the depending sash are suspended thereby.

45 8. In a window construction, a frame, a sash slidably mounted therein, a wedge-shaped member positioned therebetween and normally held in engagement with said sash and said frame, said wedge-shaped member 50 having a greater extent of surface in engagement with said frame than with said sash so that when said sash is slid in either direction relative movement will tend to take place between said wedge-shaped member and said sash.

55 9. In a window construction, a frame, a sash slidably mounted therein, a wedge-shaped member positioned therebetween and normally held in engagement with both of 60 said parts, a portion of the surface of said wedge-shaped member adjacent said sash being removed whereby the same has less surface exposed to said sash than to said frame, so that when said sash is slid in either direction relative movement will tend to take

place between said wedge-shaped member and said sash.

10. In a window construction, a frame, a sash slidably mounted therein, said sash having its side stile provided with a groove tapering in depth from end to end thereof, a clog lying in said groove and being tapered in a direction opposite from the taper of said groove and interposed between a wall of said groove and said frame, and means for reciprocating said clog to permit the sash to slide in its frame.

11. In window construction, in combination, a frame, a sash having a channeled stile slidably mounted in said frame, a strip secured to said frame and extending into one of the channels of said stile and a clog interposed between said strip and a wall of said channel for normally securing the sash frictionally to the frame.

12. In window construction, in combination, a frame, a sash having a channeled stile slidably mounted in said frame, a strip secured to said frame and extending into a channel of said stile, a clog interposed between said strip and a wall of said channel, means for normally maintaining said clog in frictional engagement with each of said parts, and means for reciprocating said clog to release said sash.

13. In a window construction, a frame, a sash slidably mounted between the jambs thereof, wedge means located in a tapering groove in said sash and interposed between and engaging said sash and said frame normally to frictionally lock the sash against sliding in one direction but adapted to permit sliding of said sash in an opposite direction.

14. In a window construction, a frame, a sash slidably mounted between the jambs thereof, wedge means located in a tapering groove in said sash and interposed between and engaging said sash and said frame normally to frictionally lock the sash against sliding in one direction but adapted to permit sliding of said sash in an opposite direction, and means for moving said wedge means, whereby the sash may be slid in either direction.

15. In a window construction, a frame, a sash slidably mounted between the jambs thereof, wedge means interposed between and engaging said sash and said frame normally to frictionally lock the sash against sliding in one direction but adapted to permit sliding of said sash in an opposite direction, a positive lock for securing said sash to said frame, said wedge means and said positive locking means being provided with means which at a single operation may be manipulated to move said parts thereby to release said sash.

16. In window construction, in combination, a frame, a sash, the side stile of which

has a tapered recess extending longitudinally thereof, a wedge member located within said recess and interposed between and engaging said frame and a wall of said recess, a device 5 for positively locking said sash to said frame, and means connected with said wedge member and said positively-locking means, whereby at a single operation said parts may be moved to free the sash and permit a free sliding movement thereof.

17. In a window construction, a frame provided with a projecting member, a sash

slidably mounted between the jambs of said frame and having a channeled stile, the edges of which take about said member, a clog carried by said sash and interposed between said member and a wall of the channel of said sash, and means tending to raise said sash and simultaneously actuate said clog to prevent such movement. 15
